UNITED STATES PATENT OFFICE.

RACHEL MYERBERG, OF BALTIMORE, MARYLAND, ASSIGNOR TO LOUIS WOLF AND ISADORE MYERBERG, BOTH OF BALTIMORE, MARYLAND.

HEEL PAD AND ATTACHMENT.

Application filed September 19, 1924. Serial No. 738,583.

To all whom it may concern:

Be it known that I, RACHEL MYERBERG, a citizen of the United States of America, residing in the city of Baltimore, State of Maryland, have invented certain new and useful Improvements in Heel Pads and Attachments, of which the following is a specification.

The present invention relates to rubber and similar pads for attachment to the heels of shoes and particularly to the means of attaching a rubber heel to the high wooden heels of ladies' shoes, though it is capable of general application as a means for attaching pads to boot and shoe heels.

The ordinary method of attaching rubber heels is not available as a means for attaching rubber pads known as rubber heels to the wooden heels of ladies' shoes, as the nails which are ordinarily used for this purpose split the wood and destroy the heels. The present invention not only overcomes this difficulty but provides attaching means for pad which is permanently secured to the heel, so that after the first pad is worn out, the second one and all subsequent sets of pads may be attached to the heel almost instantaneously, the old pad being removed with equal facility and without in any way injuring the heel.

It is of further importance that the entire operation of applying the first pad and all subsequent pads may be performed by a person wholly inexperienced in the shoe-making and repairing arts and without special tools or other appliances, and that the bottom or wearing surface of the pad is left intact without protruding metal parts which would tend to scar hardwood floors and destroy carpets and the like, and without openings or depressions which tend to reduce the wearing surface.

The device consists of a screw-threaded stud which is short and of large diameter, which is secured to the heel, projecting therefrom to be engaged by a corresponding screw-threaded socket which is embedded in the pad when it is molded prior to vulcanization, providing a screw-threaded opening in the upper surface of the pad, leaving the lower or wearing surface intact, the socket being spaced upwardly from the

wearing surface of the pad a distance equal to substantially half the thickness of the pad. The socket is provided with a laterally projecting flange or equivalent member which in the form shown is apertured and the heel is preferably punctured to receive a small brad or tack preferably registering with the hole in the flange. Also the socket is spaced downwardly from the top surface of the pad to permit the latter to be drawn up closely against the heel.

The stud is provided with prongs which enter the heel to prevent rotation of the stud, and is centrally apertured to receive a small screw which is driven up into the heel. When the stud is thus attached, the socket in the pad is engaged with the thread on the stud and the pad is screwed up against the bottom of the heel, a brad being then driven through the hole or puncture in the pad and into the heel to prevent rotation of the pad relatively to the heel.

In the accompanying drawing I have illustrated a heel with a pad and attaching means therefor in accordance with my invention in the preferred form.

In the drawing—

Figure 1 is a side elevation of a ladies' high wooden heel with the pad attached, showing the pad and attaching means in a general way.

Figure 2 is a section on the line 2, 2 of Figure 1 taken at right angles to the plane of Figure 1 and looking in the direction of the arrow.

Figure 3 is an elevation of the stud which is secured to the heel to engage the socket in the pad, the other parts being removed.

Figure 4 is a top plan of the stud and socket engaged with each other and separated from the heel and pad.

Figure 5 is a section on a reduced scale taken on a plane parallel to the section, Figure 2, showing the heel and the stud, the pad and socket being removed.

Figure 6 is a corresponding section of the pad and socket.

Figure 7 is a top plan of the pad and socket assembled; and

Figure 8 is a bottom plan of the pad showing the brad hole.

Referring to the drawings by numerals,

each of which is used to indicate the same or similar parts in the different figures, the device of the invention, as shown, is applied to a high wooden heel 1, such as is generally used on ladies' dress shoes. The rubber or similar pad 2 is attached by means of a screw-threaded stud 3 secured to the heel and a correspondingly screw-threaded stud 4 seated in the pad. The stud 3 as shown is short in proportion to its diameter, which latter is large in proportion to the diameter of the heel, the diameter of the stud in the form of the invention shown being approximately one-third of the diameter of the heel, and the stud is provided at each side of its upper surface with upwardly projecting prongs 5 and 6, and it is further centrally apertured and counter-sunk from below to receive a small slotted wood screw 7 or similar fastening means.

The co-operating socket 4 is preferably inserted in the mold when the latter is being filled in the formation of the heel pad prior to vulcanizing, the socket being vulcanized into the heel. The socket member is provided with a laterally projecting member 8 shown in the form of a flange having spaced depressions or apertures 9 through and into which the rubber may be forced, tending to prevent rotation of the socket, and the heel may to advantage be further apertured or punctured at 10 in alignment with one of the openings 9, or this opening 10 may be omitted, the object of the same being for convenience in locating the brad or tack 11 to be driven through the pad and through the projection 8, passing through one of the apertures 9 and seated in the heel 1 as shown in Figure 1 and in dotted lines in Figure 2.

When the shoe comes to the shop for the application of the rubber heel, the preliminaries having been attended to in accordance with the circumstances, the stud 4 is first affixed to the heel of the shoe, which may be of wood or any suitable material, by driving the prongs 5 and 6 into the bottom surface of the heel, hitting the bottom surface of the stud 12 one or more sharp blows with a hammer for this purpose. A small hole is then made in the centre of the heel in alignment with the central opening 13 in the stud 4, and a small wood screw or similar fastening is inserted in the heel, being passed through the opening 13 in the stud 12 and turned in flush with the top surface 12 of the stud, being otherwise turned up tight against the surface of the stud which it contacts. The pad 2 is then affixed by engaging the threads 14 of the stud with the threads 15 of the socket, and turning the pad up tight against the bottom surface of the heel. The attachment of the pad to the heel is then completed by driving the brad or tack 11 through the pad which is

preferably provided with a positioning hole 65 10 registering with one of the openings 9 in the flange or laterally projecting member 8 and into the heel proper 1. It will be apparent that when thus secured, the heel cannot be detached accidentally or in any way 70 rotated. It will also be noted that the socket member 4 is preferably depressed slightly below the surface of the heel, so that the latter may be screwed up and compressed against the heel without contact of the metal 75 parts with each other, which would tend to space the pad away from the surface of the heel.

It is also apparent that both in the first instance and subsequently with great facility the heel may be applied by anyone not necessarily skilled in the manufacture or repair of shoes. It is therefore available for sale in the retail stores, in addition to being attractive to repairmen on account of the 80 fact that it can be applied with the minimum of danger of splitting or defacing the heel, and with great ease and despatch, and that the attachment thus effected is permanent until it is desired to remove the pad, 85 when it can be removed and replaced almost instantaneously.

I have thus described specifically and in detail a single embodiment of my invention in order that the nature and operation of the 90 same may be clearly understood; however, the specific terms herein are used descriptively rather than in a limiting sense, the scope of the invention being defined in the 95 claims.

What I claim and desire to secure by Letters Patent is:

1. In combination with a pad adapted for attachment to the heel of a shoe, a threaded socket seated in the pad and having a laterally projecting portion within the pad, the bottom of the pad being intact, a threaded stud having upwardly projecting prongs adapted for insertion in the heel and a central aperture adapted to receive a screw to be inserted in and engage the heel, the laterally projecting member being adapted to engage a brad to pass through the pad and into the heel.
2. In combination with a pad adapted for attachment to a shoe heel, of a threaded socket seated in the pad, the bottom surface of the pad being intact and the socket being spaced inwardly from the upper surface of the pad, and a threaded stud with upwardly projecting prongs adapted to engage the heel, the stud having a central aperture adapted to receive a fastening member to be passed through the stud and inserted in the heel.
3. In combination with a pad adapted for attachment to a shoe heel, of a threaded socket seated in the pad, the bottom surface

of the pad being intact and the socket being spaced inwardly from the upper surface of the pad, and a threaded stud with upwardly projecting prongs adapted to engage the heel, the stud having a central aperture adapted to receive a fastening member to be passed through the stud and inserted in the heel, the socket having a laterally extending

portion within the pad with means adapted for engaging a nail. 10

Signed by me at Baltimore, Maryland,
this 17th day of September, 1924.

RACHEL MYERBERG.
